ABSTRACT

A die is mounted in a roller press by means of sprung clamping segments, which can be eased by means of hydraulic jacks for replacing the die.

ROLLER PRESS

This invention relates to a roller press comprising a die mounted on a column, said column being arranged to be driven for rotation about a stationary shaft mounted in a frame and having at least one press roller co-operating with said die, the die being secured to the column by means of movable clamping segments for the die to be mounted free of play relative to the column.

Conventionally, in such a roller press, the die is retained by means of firmly tightened screws, as is known, for example, from Dutch Patent application No. 67.05226, published Nov. 7, 1967. With such a construction, replacement of the die is time-consuming and cumbersome.

It is an object of the present invention to provide an improved construction for mounting the die in a roller press of the kind defined in the opening paragraph of this specification.

According to the invention, there is provided a roller press comprising a die mounted on a column, said column being arranged to be driven for rotation about a stationary shaft mounted in a frame and having at least one press roller co-operating with said die, the die being secured to the column by means of movable clamping segments for the die to be mounted free of play relative to the column, characterized in that the clamping segments can be maintained in the clamping position by spring means, there being provided adjusting means for easing the clamping segments against the spring action for replacing the die.

It is thus achieved that the die can be released from the column by simply overcoming the spring forces, and can also be rapidly set up.

To ensure proper centring of the die even in the released position, the movable clamping segments may peripherally alternate with fixedly mounted centring segments, which may be provided with follower means for transmitting at least part of the driving forces to the die.

In an effective embodiment, the clamping segments can be controlled by means of a thrust ring axially movable relatively to the column, while preferably the adjusting means comprise a plurality of hydraulic jacks spaced concentrically around the column and mounted on a base, said jacks being spaced from said thrust ring in an inoperative position, but being capable of maintaining the clamping segments in the eased state through said thrust ring in an operative position. By virtue of this construction, when the die is fixed, the connection between the stationary part and the rotary part of the adjusting means is broken, which makes possible a very simple construction of the adjusting means.

To prevent the forces occurring during the releasing of the die from being transmitted to the bearings of the rotary column, the base of the hydraulic jacks may be axially sprung in the frame, the arrangement being such that, in the operative position of the jacks, said base is urged against an abutment on the column against the spring action.

Some embodiments of the invention will be described, by way of example, with reference to the accompanying drawings. In said drawings,

FIG. 1 is a cross-sectional view of a part of a roller press provided with die mounting means according to the invention, taken on the line I — I of FIG. 2, the left-

hand side of the figure showing the relative positions of the elements in the tightened position of the die, and the right-hand side of the figure in the eased position of the die;

- 5 FIG. 2 is a partial top view of FIG. 1;
 FIG. 3 is a partial bottom view of FIG. 1;
 FIG. 4 shows a detail on the line IV — IV of FIG. 3;
 FIG. 5 shows a diagram of an hydraulic circuit for the operation of hydraulic jacks; and
 10 FIG. 6 shows a detail of a modified embodiment of the clamping segments and the control of same.

A die 1 for a roller press is mounted on a column 2 driven for rotation. For the sake of simplicity, a stationary shaft which mounts the column 2 for rotation by means of bearings as shown for example in Dutch Pat. application No. 67.05226, have been omitted from the drawing. The die 1 is mounted on the upper end of column 2 by means of fixed centering segments 3 and axially movable clamping segments 4. The clamping segments 4 are connected to a thrust ring 6 by means of bolts 5. Interposed between the upper end of the column and thrust ring 6 are a plurality of springs 7. Thrust ring 6 can be axially displaced relative to column 2 by means of hydraulic jacks 8. Hydraulic jacks 8 are supported on a base plate 9, which in turn is mounted in a frame 10 of the roller press. The lower end of column 2 carries a pulley 11.

The fixed centering segments 3 are secured in the upper end of column 2 by means of filister head screws 12. The heads of these screws are countersunk in corresponding recesses in die 1, so that part of the driving forces can be transmitted to the die through these heads. Clamping segments 4 have a horizontal face 13 and a cylindrical face 14 contiguous with corresponding surfaces of die 1. On the outside, the clamping surfaces have a frustoconical surface corresponding with a similar surface 15 in the head of column 2. The bolts 5 are screwed into the underside of clamping segments 4, on the one hand, and are fixed on thrust ring 6 by means of a shoulder and a nut, on the other. In the example shown, the springs 7 take the form of rubber springs and are arranged around centering pins 16. These centering pins (also see FIG. 4) are mounted in thrust ring 6 and define the stroke of the thrust ring relative to the head of column 2.

Hydraulic jacks 8 each comprise a plunger 17 with a piston 18 thereon, cylinder 19, and compression spring 20. As will be seen from FIG. 5, the hydraulic jacks, six in the example shown, may be connected to a common duct 21 including a pressure gauge 22. This duct can be provided with oil-under-pressure from an oil pressure pump 24 with by-pass 25.

Base plate 9, on which jacks 8 are mounted, is in turn resiliently mounted in frame 10 by means of a plurality of supports 26 and bolts 27 and by means of springs 28. The springs 28 bear on supports 29, bolted to frame 10. Bolts 27 are secured in supports 29 as well.

In the position of die 1 in column 2 as shown in the left-hand side of FIG. 1, clamping segments 4 are drawn into conical recess 15 of the head of column 2 under the influence of compression spring 7 through bolts 5 and thrust ring 6. The clamping segments 4 will tend to move inwardly, as a result of which the die will be retained by the clamping surfaces 14 of segments 4. In this position, the heads of bolts 12 lie in the corresponding recesses in die 1, so that the driving forces can at least in part be transmitted to the die. In this po-

sition, thrust ring 6 is clear of the ends of plungers 17 of jacks 8, so that when the column 2 is driven through pulley 11, the assembly can freely rotate.

For the removal of a die, the roller press is stopped, whereafter oil-under pressure is passed to jacks 8 by means of pump 24 through valve 23 and ducts 21. This will urge plunger 17 with pistons 18 outwardly into contact with thrust plate 6 against the action of springs 20. Thrust plate 6 is moved upwards co-axially relatively to column 2 against the action of springs 7. This will also force die 1 with clamping segments 4 to move upwardly, easing conical surfaces 15 of the head of the column and of the clamping segments away from each other, so that clamping segments 4 can be moved slightly outwardly, and die 1 is released. The die can now easily be removed from the press and replaced by another. In this position the die will be centered relatively to column 2 by fixed centering segments 3. In the operative position of jacks 8, whereby clamping segments 4 have been released, not only will the forces generated in the jacks tend to move thrust plate 6 upwardly, but they will tend to move the base plate 9 downwardly as well. The base plate can slightly compress springs 28 through supports 26, whereby the base plate comes to rest on the upper edge of pulley 11. The thus occurring forces are further exclusively transmitted from the jacks through base plate 9 and, pulley 11 into column 2, so that not only are the unillustrated bearings mounting column 2 on the shaft (not shown) maintained free of additional loads, but the other parts, such as frame 10, are not subjected to undue forces which may occur during the releasing of clamping segments 4. When the oil pressure is released, plungers 17 will be retracted under the influence of springs 20, and thrust plate 6 will resume the position shown in the left-hand side of FIG. 1 under the influence of springs 7, so that clamping segments 4 will again clampingly engage a die.

It should be noted that, although springs 7 and hydraulic jacks 8 are used in the embodiment described above, other clamping means, for example, a pawl system or mechanical jacks, may be used, while the hydraulic jacks may be replaced by other force-transmitting means, such as levers and the like.

In the variant embodiment of FIG. 6, the die is retained by cleats 26 engaging in a peripheral groove of the die. Springs 7 are disposed on an extension of each cleat 26 and bear on supports 27, bolted to column 2 in known manner not shown.

Column 2 is provided with guide means for cleats 26 and for axially movable pins 29. Pins 29 have recessed cam surfaces 30 arranged to co-operate with shafts 31 on cleats 26. Pins 29 are all mounted on a thrust ring 32 which via an auxiliary ring 33 can be displaced by jacks 8, so that the cleats can be moved outwardly against the action of springs 7. In FIG. 6, the jacks are mounted on a support plate 34 of frame 10.

I claim:

1. Apparatus for releaseably clamping a die of a roller press and like structure on a driving column for rotation therewith wherein said die and said column have telescopically arranged surfaces and said column is mounted in a frame, said apparatus including axially and radially movable clamping segments each having a first surface in radial thrust engaging relation with said die and second surfaces cammingly reacting relative to said column, resilient means normally urging said sec-

ond surfaces in a direction to effect a camming action urging said telescopically arranged surfaces radially together, and adjusting means for selectively overcoming said resilient means and releasing said clamping segments to facilitate the removal of said die, the clamping segments peripherally alternating with fixedly mounted centering segments.

2. A roller press according to claim 1, wherein all of the clamping segments are controllable by a single thrust ring axially movable relatively to the column, said thrust ring being a part of said adjusting means.

3. Apparatus for releaseably clamping a die of a roller press and like structure on a driving column for rotation therewith wherein said die and said column have telescopically arranged surfaces and said column is mounted in a frame, said apparatus including axially and radially movable clamping segments each having a first surface in radial thrust engaging relation with said die and second surfaces cammingly reacting relative to said column, resilient means normally urging said second surfaces in a direction to effect a camming action urging said telescopically arranged surfaces radially together, and adjusting means for selectively overcoming said resilient means and releasing said clamping segments to facilitate the removal of said die, the adjusting means comprising a thrust ring axially movable relatively to the column for controlling said clamping segments and a plurality of hydraulic jacks mounted on a base and concentrically spaced about the column, said jacks being spaced from the thrust ring in an inoperative position, and capable of maintaining the clamping segments in the eased state through said thrust ring in an operative position.

4. Apparatus according to claim 3, wherein the hydraulic jacks have a base axially resiliently mounted in the frame, the arrangement being such that, in the operative position of the jacks, the base is urged against an abutment on the column against the action of said resilient means, so that the forces active to ease the clamping segments are transmitted virtually exclusively through the column.

5. A roller press according to claim 3 wherein the hydraulic jacks have a base axially resiliently mounted in the frame, the arrangement being such that, in the operative position of the jacks, the base is urged against an abutment on the column against the action of said resilient means, so that the forces active to ease the clamping segments are transmitted virtually exclusively through the column.

6. Apparatus according to claim 1 wherein said fixedly mounted centering segments have follower means for transmitting at least a part of the driving force from said column to said die.

7. A roller press comprising a die mounted on a rotatable column carried by a frame, the die being secured to said column free of play relative to said column by movable clamping segments engaged with said die and movable relative to said column, resilient means constantly urging said clamping segments to a die clamping position, and adjusting means associated with said resilient means for easing the effect of said resilient means on said clamping segments, fixedly mounted centering segments alternating with said clamping segments, and follower means operatively associated with said centering segments for at least in part transmitting a driving force from said column to said die.

8. A roller press comprising a die mounted on a rotatable column carried by a frame, the die being secured to said column free of play relative to said column by movable clamping segments engaged with said die and movable relative to said column, resilient means constantly urging said clamping segments to a die clamping position, and adjusting means associated with said resilient means for easing the effect of said resilient means on said clamping segments, said adjusting means com-

prising a thrust ring axially movable relatively to the column for controlling said clamping segments and a plurality of hydraulic jacks mounted on a base and concentrically spaced about the column, said jacks being spaced from the thrust ring in an inoperative position, and capable of maintaining the clamping segments in the eased state through said thrust ring in an operative position.
